UNITED STATES PATENT OFFICE.

HENRY L. GERSTENBERGER, OF ROSELLE, NEW JERSEY, ASSIGNOR TO STANDARD OIL COMPANY, OF NEW YORK, N. Y., A CORPORATION OF NEW JERSEY.

METALLIC DRUM.

1,413,907.

Specification of Letters Patent. Patented Apr. 25, 1922.

Application filed April 28, 1920. Serial No. 377,350.

To all whom it may concern:

Be it known that I, HENRY L. GERSTENBERGER, a citizen of the United States, residing at Roselle, in the county of Union and 5 State of New Jersey, have invented a new and useful Improvement in Metallic Drums, of which the following is a specification.

The present invention relates to improvements in metallic drums, and is fully described in the following specification and illustrated in the accompanying drawings, in which—

Figure 1 is a perspective view of a drum embodying the present invention;

15 Figure 2 is a sectional detail view showing the chime and head of the drum;

Figure 3 is a detail sectional view of a modified form of construction;

20 Figure 4 is a detail sectional view through the head of a drum of the same form of construction as shown in Figure 2; and

Figure 5 is a detail sectional view through the head of the drum, the form of construction being the same as that of Figure 3.

25 Referring more particularly to the construction of the drum, the numeral 10 indicates the body of a drum, which may be substantially cylindrical in form and provided with hoops 11, which may be, if de-

30 sired, rolled into the body of the drum. Near each end the body of the drum is rolled or pressed outwardly to form a narrow ledge, or shoulder, 12, upon which rests the sheet or head 13 of generally circular form. A

35 weld is formed entirely around the head at its point of contact with the chime portion of the body above the shoulder 12, the added weld metal being indicated by the numeral 14. The means for attaching the head of 40 the drum, as above described and illustrated in the drawings, is the same for both ends of the drum.

The chime of the drum extends upwardly 45 above the head of the barrel and is, in the form of construction shown in Figures 2 and 4, rolled over a steel hoop 15 of circular cross-section. The chimes at both ends of the drum are reinforced in the same manner. In the head of the drum the spuds for

50 the bung and vent holes are seated upon conical projections formed or pressed in the head, the interior surfaces of which projections are concave, so that on turning over the barrel to empty the same, its contents will all 55 drain perfectly through the bung or vent holes. Annular seats are formed in the

bases of the bung and vent hole spuds 16 and 17, respectively, which seats engage the openings provided in the head in such manner that the surfaces of the spuds on the interior of the drum are flush with the contiguous surfaces of the drum-head, and form therewith a continuous conical surface. A weld 18 around the bung hole spud 16 secures it in position, and a similar weld 19 secures the vent hole spud 17 in position. The plugs 20 and 21 are screwed into and close the bung and vent holes in the respective spuds, suitable gaskets 22, 22 being provided for both. The proportions of the 70 parts are such that the outer surfaces of the bung and vent hole spuds are below the level of the top of the chime. Near the base of the chime, at a point below the openings of the bung and vent hole spuds, a plurality 75 of openings 23, 23, are formed in the chime, and prevent the accumulation of liquid on the head of the drum to a level which would permit it to enter the bung and vent holes.

In the form of construction illustrated in 80 Figures 3 and 5, the construction of the heads of the drum, the means for securing them to the drum, and the construction of the bung and vent hole parts are substantially the same as has been described in connection with the construction of Figures 2 and 4. In this form of construction, however, the upper portion of the chime is reinforced by turning or spinning it inwardly over the top of a circular ribbon, or hoop, 90 24, of flattened cross-section. At suitable intervals around the chime, grommets 25 pass through the hoop 24 and the chime, and secure these parts together. These grommets are positioned below the top of 95 the bung and vent holes, the openings through the grommets thereby preventing water accumulated on the head of the drum from entering it.

By the construction of the present invention provision is made for the complete emptying of the contents of the drum, and at the same time their contamination during pouring or on opening of the bung and vent holes is substantially entirely prevented.

Although the present invention has been described in connection with the specific details of the apparatus illustrated, it is not intended that these details shall be regarded 110 as specific limitations upon the scope of the process, except in so far as included in the

accompanying claims as interpreted by the prior art.

I claim:

1. In a metallic drum, a body, a head seated within said body and provided with a conical upwardly inclined projection extending above the plane of the edge of the head which contacts with the wall of the body of the drum, the edges of said projection forming an opening, a spud seated in the said opening and having its lower end inclined to make flush contact with and a continuation of the conical interior surface of the projection, and a closing plug adapted to seat in said spud.
2. In combination, a drum body formed near its end with a shoulder and extended beyond said shoulder to form a chime, a reinforcing hoop within the chime, a head seated upon the said body shoulder, said head being provided with interiorly con-

cave conical projections, spuds seated upon the said projections and having their interior surfaces flush with the internal surfaces of said projections and of like conicity, the openings of said spuds being below the top of the chime, closures for said openings, apertured means for securing the chime and reinforcing hoop together, said means being so positioned that the openings therethrough are below the level of the openings of the spuds.

3. In combination, a drum body, a head having an opening therein, the drum body being extended beyond the head to form a chime, reinforcing means adjacent the chime, apertured means for securing the chime and reinforcing means together, said securing means being so positioned that the openings therethrough are below the level of the opening in the head.

HENRY L. GERSTENBERGER.
